(57) **CLAIM**

The ornamental design for a passenger seat, as shown and described.

DESCRIPTION

FIG. 1 is a front perspective view showing our new design of a passenger seat;

FIG. 2 is a rear perspective view of the passenger seat of FIG. 1;

FIG. 3 is a front view of the passenger seat of FIG. 1;
FIG. 4 is a rear view of the passenger seat of FIG. 1;
FIG. 5 is a right side view of the passenger seat of FIG. 1; and

FIG. 6 is a left side view of the passenger seat of FIG. 1.

FIG. 7 is a top view of the passenger seat of FIG. 1; and,

FIG. 8 is a bottom view of the passenger seat of FIG. 1.
In FIGS. 1-8, broken lines indicate environmental structure that forms no part of the claimed design.

1 Claim, 8 Drawing Sheets
